United States Patent Office

Des. 219,007

Patented Oct. 27, 1970

219,007

BAG HOLDER

John Terrence Clifton, Willowdale, Ontario, Canada, assignor to Multipak Ltd., East Montreal, Quebec, Canada

Filed Mar. 7, 1969, Ser. No. 16,112

Term of patent 7 years

Int. Cl. D8—99

U.S. Cl. D8—259

FIG. 1

FIG. 2

FIG. 3

FIG. 1 is a perspective view of a bag holder showing my new design;

FIG. 2 shows a perspective view of the reverse side of the bag holder;

FIG. 3 shows an end view of the bag holder.

I claim:

The ornamental design for a bag holder, as shown and described.
